UNITED STATES PATENT OFFICE.

JAMES H. DYETT, OF BROOKLYN, NEW YORK, ASSIGNOR TO W. J. ANDERSON, OF BROOKLYN, NEW YORK.

STRIP-MOISTENING MACHINE.

No. 896,443.

Specification of Letters Patent. Patented Aug. 18, 1908.

Application filed June 12, 1908. Serial No. 438,251.

To all whom it may concern:

Be it known that I, JAMES H. DYETT, a citizen of the United States, residing at Brooklyn, in the county of Kings and State 5 of New York, have invented certain new and useful Improvements in Strip-Moistening Machines, of which the following is a specification.

My invention relates to machines in which a 10 roll of paper or other material is supported centrally in a vertical position on a horizontal pin or shaft. As the strip of paper is drawn out the roll revolves on the shaft, and unless the revolution of the roll is controlled, its 15 tendency is to continue turning by the impetus gained by drawing out the strip, causing a surplus of the unwound paper and interfering with its proper use.

In gummed strip moistening machines, 20 having a strip cutter attached, it is very important that a brake should be applied to the roll, of sufficient force to produce some tension of the strip, when it is drawn against the teeth of the cutter, as well as to prevent a 25 surplusage of the paper. In order to secure the proper degree of resistance to the roll, I provide a friction cover, one for each roll, if the machine contains a plurality of rolls, which engages the roll by gravity.

30 The accompanying drawing illustrates my invention, like characters of reference denoting corresponding parts in the several views.

In the drawing, Figure 1 shows a side elevation of a gummed strip moistening machine, equipped with my invention. Fig. 2 35 is a side elevation of the friction cover, alone. Fig. 3, is a rear elevation of a two roll machine, partly in section on line $x-x$ of Fig. 1, and having one roll reduced in circumference.

40 The figure 5 denotes the base, and 6, 6, the vertical roll supports of a strip moistening machine, carrying two rolls. Bearings 8, on the supports 6, 6, are provided for the ends of the shaft 7, on which the rolls 10, of gummed 45 paper, or other material freely revolve.

12 is a water bowl in which a sponge or some equivalent material 13, is placed, on which the gummed strip is moistened; and

14 is a cutter on which desired lengths of the strip, are cut off.

50 16 denotes the cover of each roll. The upper part of this cover is preferably arched to conform in some degree to the periphery of the roll. In each side of the cover is a vertical slot 18, open at the bottom and extending 55 almost to the top of the cover. This slot is sufficiently wide to admit the shaft loosely 60 therein. The cover rests directly upon the upper surface of the roll, and acts as a friction brake to the roll, its sides having the slots 18, 65 extending downwards below the shaft 7, and thus permitting the vertical movement of the cover on the shaft made necessary by the varying size of the roll, and at the same time preventing any unintentional displacement 70 of the cover by the turning of the roll within it. It is evident without further explanation 75 that this cover will exert an effective and uniform action on the roll, from the highest to the lowest points of its periphery and until all the paper is drawn off.

What I claim and desire to secure is—

1. In a machine of the character described, 80 a base, vertical supports thereon, a shaft journaled on said supports, a roll on said shaft, a cover resting on said roll, vertical slots in each side of said cover open at the bottom and extending almost to the top of said cover and sufficiently wide to loosely admit said shaft and allow a vertical movement of said cover thereon.

2. In a strip moistening machine having a base and supports thereon, shaft bearings on said supports, a shaft in said bearings, a roll on said shaft, and a cover on said roll having vertical slots in its sides extending from the bottom to near its top, said slots being adapted to loosely admit said shaft and permit vertical movement of said cover thereon.

85 In testimony whereof I affix my signature, 90 in presence of two witnesses.

JAMES H. DYETT.
